FRANCE

ELECTRIC ORGAN OPERATING BY MEANS OF ELECTRODE VALVES

Application filed June 30, 1931, Serial No. 547,982, and in France November 15, 1930.

It is a known fact that musical sounds can be produced by means of oscillations of musical frequency in oscillating circuits, which are put in use by the operation of 5 keys. The great difficulty in obtaining simultaneous sounds consists in avoiding interference between the harmonics, but if it is further desired to obtain all the variations of playing, shading, and the like, as in 10 a pipe-organ, particular combinations must be used, and chiefly if the number of loud-speakers is to be reduced.

The present invention relates to particular arrangements of oscillating circuits, 15 with electrode valves and various controlling and regulating devices for the obtainment of all the operating features of a pipe organ.

The principle employed consists in the use of a valve for each note and for one key, and 20 all the notes of the same kind in each octave (or in each group of notes of the keyboard divided into like groups) are connected to a common circuit, each circuit leading to an amplifier and then to a loud-speaker. For 25 the keyboard divided into octaves, including the accidental notes, there will thus be 12 circuits and 12 loud-speakers.

If only a single powerful loud-speaker is to be used, each of the 12 circuits is connected 30 to a unit primary of a transformer having a single secondary which is connected to a powerful amplifier and loud-speaker.

A given valve may be further arranged so 35 as to produce several notes at will, for instance by mounting in a grid circuit of a valve having one or more grids, a capacity shunted by a high resistance, which is normally in short-circuit when the valve gives 40 the normal note, but will be put in operation by another key, suitable precautions being taken to avoid untuning the valve.

With valves having several grids, it is 45 possible to use auxiliary grids to obtain a certain impedance of the circuits in order

to produce the proper variations without affecting the purity of the note.

The transposition of an entire keyboard (the organ may have several of these) or of a group of notes, is obtained by a movable 50 element carrying strips of soft iron or like devices for the electric control of the parts of the circuits, such as the self-induction coils. This will constitute a "vox celesta" with beats which are regulated at the de- 55 sired rate by the action of the movable element.

Changes of tone quality may be obtained by suitable means acting upon the number and quality of the harmonics, but preferably 60 by electro-magnetic saturation of the iron of the transformers or of the loud-speakers of the excitation type. In fact, when a core is saturated, harmonics will appear in 65 the circuit of the windings on the said core.

The volume of sound is regulated by groups of notes, by separating or bringing together, in the transformer affected by the group, the multiple primaries cooperating 70 with the single secondary, thus changing the induction effects. With a suitable resistance which is put in use at the proper time, the sonority of the pedal notes will be proportioned to the notes of the keyboard.

In order to obtain an easy and regulated 75 attack of the note, a loud-speaker of the excitation type is used, and the valve sends the exciting current with a certain delay with reference to the supply of musical currents to the said movable element.

To avoid impact in the loud-speaker, the key with its contacts may be placed in the filament circuit of the valve, when the key sends the heating current, the calorific inertia of the filament produces the note more smoothly than if the key is in the circuit of the grid or the plate. The extra current of rupture is avoided by using a high resistance in shunt, which operates the valve 85 at a low voltage, or by using a capacity. 90

If the key is used with the grid or the plate, the cracking sound of the diaphragm can be prevented by means of contacts of the proper character and form, which will 5 put the oscillating circuit in operation, or in short-circuit during the periods of silence, and thus the plate circuit is never broken.

The said contacts, as well as all the others of the apparatus, are preferably operated by 10 electro-magnetic relays. The rate of opening or closing of the circuit will thus be independent of the action of the fingers upon the keys. It will be determined in advance by the exciting current, so as to produce 15 the best result, to prevent the cracking sound and to give the absolute effect of a pipe-organ.

Shading of sound is obtained by fixed or 20 adjustable resistances, put in by the keys, which can optionally regulate the same, thus affording all desired shading for a given note or group of notes.

The accompanying drawings show by way 25 of example various embodiments of the invention.

Fig. 1 shows the arrangement of a typical 30 octave of the organ.

Fig. 2 shows the arrangement of another 35 octave.

Fig. 3 relates to the use of an amplifier 40 and a loud-speaker per circuit.

Fig. 4 indicates the use of a single loud-speaker for the organ.

Fig. 5 relates to a modified arrangement 45 with a single loud speaker.

Fig. 6 shows the arrangement of a valve 50 producing two different notes.

Figs. 7 and 8 relate to arrangements of a 55 two-grid valve.

Fig. 9 represents a transposing device.

Fig. 10 relates to the regulating of the 60 attack by the loud-speaker.

Fig. 11 indicates the regulating of the 65 volume of sound.

Figs. 12 and 13 show the control of shading 70 by the key.

Fig. 1 (the organ being divided into octaves) shows a typical octave, for instance 75 1. Each note has its lamp or valve L its oscillating circuit C, its key T with the contact sending the musical current into the circuit F. Each note, do, do sharp, re etc., has its circuit. An adjustable laminated 80 iron core serves to tune each oscillating circuit.

Any one of the other octaves (Fig. 2), with its valve L its keys T, etc., is connected 85 to the circuits of the said typical octave. The circuits F (Fig. 3) each end at a coupling transformer, with amplifier a and loud-speaker d.

Fig. 4 shows a single transformer Tr having 90 multiple primaries and a single secondary S connected to an amplifier L' provided with its polarizing battery B and

the powerful loud-speaker D adapted to reproduce all the notes of the organ.

Fig. 5 shows an arrangement with filters b in the plate circuit in order to stop off all harmonics subject to interference. The 95 grids have a common return wire to the heating battery P. The unit primaries e are connected to the + pole of the plate battery, and they are calculated and tested in such manner that when taking account of the leakage inductance of the transformer and of the capacities distributed in the windings, there will be opposed a high impedance to the harmonics without weakening the fundamental note, thus preventing interference between harmonics, which is a source of beats and humming of a disagreeable 100 nature at low frequencies.

In Fig. 6, the valve L is arranged so as to produce two different notes. In the grid 105 circuit is a capacity E shunted by a high resistance R which is normally short-circuited by the bar M of a key T, brought back by a spring. When the key T is lowered, the bar M' connects the - pole of the plate 110 battery P to the neutral point of a resistance K in shunt upon P.

The key T gives the normal note of the valve the grid being negatively polarized and the circuit C being put in use by the 115 contact of the key T. If the player acts upon T' instead of T, the capacity n and the resistance R will act upon the grid, which produces the effect of the singing lamp. Since R might untune the lamp, its action 120 is compensated by depolarizing the grid by means of the bar M'.

This combination can be made with a valve having several grids which gives the 125 principal note and as many different notes, 130 at will, as there are grids. One may also use multi-grid valves in order to obtain several notes of different pitches and quality, optionally starting from the same oscillation.

Fig. 7 shows a two-grid valve, with the second grid connected to the plate through 135 a capacity o and an adjustable resistance r serving to vary the tonality without being used in the circuits.

In Fig. 8, the two-grid valve L' is mounted 140 in such manner that one collects the sounds by the second grid with the output transformer h. This affords a certain independence of the circuits and variations of 145 impedance of the circuit C which will not affect the pitch of the note.

In the transposing device (Fig. 9) a fixed 150 frame M carries a winding s with core n, for each note. A member G is slidable upon two rods t₁ t₂ which are under mechanical or electrical control. It carries strips I cooperating 155 with the cores n, more or less affecting the windings s according to their relative position, thus acting upon the tonality of 160

the circuits, as proportioned by the movements of G obtained for instance by a pedal.

Fig. 10 shows the means for regulating the action by a loud-speaker of the excitation type. The key T_1 controls a contact d_1 which is separated by I from the contact d_2 for closing the plate circuit and sending musical currents into the operative part E_1 of the loud-speaker E of the excitation type, 10 coming from a battery B_1 . The circuit of the loud speaker E is closed by d_2 , after d_1 and an adjustable self-induction coil S_1 serves to proportion this delay in sending current into the loud speaker E, which latter, when not excited, leaves the loud-speaker without sound.

The regulating of the volume of sound in each group of notes is effected by their transformer (Fig. 11). A core H movable 20 about its axis XY carries multiple pole-pieces 1, 2, etc. which are herein of a double cross-shape at each end, as well as a single secondary S. Fixed armatures with pole-pieces 2' cooperating with 1, 2 etc., carry 25 the primary unit parts e (the drawings show only one of these armatures). When H rotates, 1-2 etc. take adjustable positions with reference to 2' etc., thus varying the effects of induction and hence the volume of sound 30 of the group. The core H is controlled by any suitable means, using if necessary a dial with its stationary mark.

Fig. 12 shows a method of regulating the shading or expression by lowering the key 35 T which is pivoted at a. It controls a rheostat Q, preferably circular, which is branched at a suitable point of the sound circuit; Q is controlled at its end (shown by the dotted lines, optionally with speed-reduction by toothed sector, or by a pedal W 40 which can be acted upon by all the keys of a group by a member Z. The more the key is lowered, the more the resistance will be affected.

Fig. 13 shows the use of fixed resistances q which are placed in the circuit by the plates g of the key. Switches j controlled by the player serve to place in position the resistance corresponding to a shade of tone. 50 This is applicable to a note or a group of notes and the parts (such as those of Fig. 12) are situated at any suitable points on the instrument.

Having now particularly described and 55 ascertained the nature of our said invention and in what manner the same is to be performed, we declare that what we claim is:

1. In an electric organ operating by means of electrode valves, lamps with multiple 60 grids affording several notes, a capacity in the grid circuit of the valves, and a high resistance shunting said capacity.

2. In an electric organ operating by means of electrode valves, one valve for each note 65 and one key for each valve, a keyboard di-

vided into similar groups, circuits to which are connected all the notes of the same name in each group, said valves having multiple grids, and means for regulating the notes while maintaining the independence of the 70 circuits by the additional grids.

3. In an electric organ operating by means of electrode valves, one valve for each note and one key for each valve, a keyboard divided into similar groups, circuits to which 75 are connected all the notes of the same name in each group, a transposing apparatus for each group including a movable frame carrying soft iron strips, and a fixed frame carrying the self-induction coils of the circuits of the group. 80

4. In an electric organ operating by means of electrode valves, one valve for each note and one key for each valve, a keyboard divided into similar groups, circuits to which 85 are connected all the notes of the same name in each group, transformers and loud speakers in said circuits having windings providing for the magnetic saturation. 90

5. In an electric organ operating by means of electrode valves, one valve for each note and one key for each valve, a keyboard divided into similar groups, circuits to which are connected all the notes of the same name in each group, a transformer having a single secondary winding and multiple primary windings, said transformer including fixed armatures carrying the transformer primary windings, and a core provided with a plurality of pole pieces movable before 95 said fixed armatures and carrying the transformer single secondary winding. 100

6. In an electric organ operating by means of electrode valves, one valve for each note and one key for each valve, a keyboard divided into similar groups, circuits to which are connected all the notes of the same name in each group, a loud speaker of the excitation type, and means in the circuit for sending the exciting currents into the loud speaker with a certain delay. 110

7. In an electric organ operating by means of electrode valves, one valve for each note and one key for each valve, a keyboard divided into similar groups, circuits to which are connected all the notes of the same name in each group, contact means for placing the circuit in operation, circuits to which are connected all the notes of the same name in each group, a contact included in the heating circuit of the valve filament, and a key for operating said contact. 115

8. In an electric organ operating by means of electrode valves, one valve for each note and one key for each valve, a keyboard divided into similar groups, circuits to which are connected all the notes of the same name in each group, contacts for placing the circuits in operation, and electro-magnetic relays for controlling said contacts. 120 125 130

9. In an electric organ operating by means of electrode valves, one valve for each note and one key for each valve, a keyboard divided into similar groups, circuits to which are connected all the notes of the same name in each group, and resistances adjustable in said circuits and operated by the keys.

In witness whereof we have hereunto set our hands.
